REPLENISHING MECHANISM FOR LOOMS

Waldo H. Banks and Harrison N. Thibault, Hopedale, Mass., assignors to Draper Corporation, Hopedale, Mass., a corporation of Maine

Application August 1, 1958, Serial No. 752,545

10 Claims. (Cl. 139—245)

This invention relates to automatic batteries for looms for weaving, and in particular, to improvements in the replenishing means for supplying filling packages to the loom battery.

It is a general object of the invention to provide a novel magazine stop mechanism which will insure the complete removal of the supply of filling packages from each compartment of a gravity controlled compartmented magazine before permitting the next compartment of the magazine to advance to a feeding position.

It is a further object to provide a stop means which is controlled by a filling supply actuated member at the entrance end of the battery.

It is a further object to provide a stop means which may be assuredly released upon the exhaustion of the supply of bobbins having filling wound thereon in one compartment of the magazine so as to permit advancement of the magazine so that the next compartment is in feeding position above the entrance of the battery.

It is a further object to provide a stop means which includes a latch means movable to two positions and effective for maintaining a compartment aligned with the battery in each of said two positions.

It is a further object to provide a stop means which is effective to halt advancement of the magazine momentarily until a filling package has been released into the opening of the battery whereupon said stop means is actuated to a second holding position.

Further objects will be apparent from the following disclosure.

Most fly shuttle looms presently in use utilize a rotary or other battery from which a filling supply on a bobbin is automatically transferred to a shuttle as needed. This battery may contain up to about twenty bobbins which must be manually inserted into the battery and the end of the thread wound about a knob or other retaining means, thus involving considerable time and labor.

In United States Patent No. 2,778,382 there is disclosed a combined gravity and vibrational feed means making possible the supplying of a very large number of filling bobbins to the loom without the manual labor of inserting each individual bobbin. A novel bobbin container is disclosed therein which is formed into vertical compartments for vertical tiers or rows of bobbins contained therein and held in place by a retaining means at the lower end of each row. A stop means restrains advancement of the magazine until the bobbins in a particular compartment of the magazine have been exhausted at which time the magazine is advanced by gravity and normal vibration of the loom so that the next filled compartment is in position to feed bobbins to the battery and so on until the magazine is depleted of its supply. The track upon which the magazine rides is long enough to accommodate two or more of the magazines so that a second filled one may automatically move to feeding position.

According to the present invention the filling package container or magazine is preferably of the type disclosed

2

in the above-cited patent having a track system which permits gravitational advancement of the magazine. However, a novel stop mechanism has been devised which is so constructed that it will readily be forced to a release position at the proper time in spite of the weight of a part of the magazine bearing thereupon. The stop mechanism is such that it also prevents any possibility of bypassing of a filled compartment without release of bobbins therefrom. These desired results are effected by means of a latch member having two horizontally separated abutments and a fixed cam element cooperating therewith. One of these abutments delays advancement of the magazine only sufficiently long so as to enable a bobbin to be released from its compartment and to actuate an indicator door at the entrance of the battery which then causes the latch to pivot to its second or holding position at which the second abutment comes into play to prevent further advancement of the magazine.

The invention will be described in greater detail by reference to a preferred embodiment illustrated in the accompanying figures of drawings wherein:

Fig. 1 is a side elevation of the invention applied to a loom.

Fig. 2 is a side view of the stop means illustrating its position at the instant of release of a bobbin from its compartment in the magazine.

Fig. 3 illustrates the position of the stop means after a supply of bobbins has dropped into the battery and wherein the magazine is positively engaged by the stop means.

Fig. 4 is a plan view of Fig. 3.

Now referring to Fig. 1, the invention is shown applied to a loom only a small portion of which is illustrated. The right hand side of the loom has attached to it rails 10 and 11 which extend forwardly and downwardly and which support the bobbin feeding means or magazine 12, which is shown as having a supply of bobbins 13 therein. The magazine is normally advanced upon the tracks by means of gravity and the normal vibration of the loom and is shown as being retained in position by a stop means generally designated as 14 to be described in more detail hereinafter.

Upon release of the stop means bobbins drop into a battery 15 each of which is periodically transferred to a shuttle 16 in a manner well known in the art. As the bobbins are exhausted from the final compartment of the magazine, the latter is transferred by means of cross supports 17 and 18 to a second set of tracks 19 and 20 (see Figs. 1 and 4).

Except for the stop means, the magazine and its related structure have been more completely described in United States Patent No. 2,778,382 and reference is made thereto for a more detailed disclosure of such structure and it need not be repeated here.

Now referring to Figs. 2 to 4, the stop means 14 is shown as being mounted upon the track 11. A second stop means is shown at 14' mounted upon track 10 identical in structure to said first stop means except that it is reversely directed, and thus only the stop means 14 need be described in detail. The latter comprises a latch means 21 preferably metallic pivoted at 22 to a magazine trip member 23 which may be cast iron fastened to the track by means of bolts 24. The trip member comprises a horizontally inclined cam portion 25 having a recessed portion 26 therein. The cam portion is in alignment with the track so that it may be engaged by a transverse rod 27 which normally retains a tier of bobbins in a compartment of the magazine and which is movable when so engaged in a slot 28 at the side of a compartment extending rearwardly and upwardly thereof.

The latch 21 has at one end two inturned portions 29 and 30 forming horizontally separated abutments which

are engaged by the transverse rod 27 and affect movement of the magazine in a manner to be described. The recessed portion 26 is positioned on the cam in such manner that it may receive the abutment 30 when the latch element 21 is caused to pivot in that direction.

A substantially vertically extending link element 31 which is also preferably metallic is pivotally mounted at its upper end to the opposite end of the latch means by means of a pin 32 and has a slot 33 formed in its lower end.

An indicator shaft 34 is supported in bearings 35 and 36 on the upper chute C, said bearings preferably being Nyliner type bearings so that they need not be oiled. An indicator door 37 of steel or other metal is fastened to the shaft 34 approximately centrally thereof and is overbalanced by means of the indicator counterweight 38. Both the counterweight and indicator door are fixedly mounted to the shaft 34 by fastening means 39 and 40, the door having slots provided therein to permit adjustment thereof in a substantially horizontal direction in the position shown in Fig. 3.

At the end of the shaft 34 shown in Fig. 3 there is fixed a metallic link lever 41 having an extension 42 protruding therefrom and received in the slot 33. A washer 43 and cotter pin or any other retaining means (not shown) act to prevent the link member 31 from being separated from the extension 42.

An adjustable stop member 44 is threaded in a substantially vertical direction through an extension of the trip member 23 which limits movement of the link arm 31 in a downward direction.

The opening of the battery is shown at 45 and its size is determined by the vertically extending wall portions 46 and 47. The adjustability of the indicator door 37 permits a variation in the size of this opening, which should be about $\frac{1}{8}$ " to $\frac{3}{16}$ " larger than the diameter of the filling 48 on the bobbin.

The operation of the novel stop means is as follows:

One or more magazines filled with bobbins is placed upon the tracks 10 and 11 to the right of the stop means as viewed in Fig. 1. As the loom is started vibrations cause the magazine to move slowly toward the stop. As the retaining transverse rod 27 of the first compartment is caused to move upwardly and rearwardly in its respective slots 28 due to the inclination of the cam element 25, at approximately the position shown in Fig. 2, the bobbins retained by the rod 27 are released into the opening of the battery and forward movement of the magazine is momentarily halted by means of the abutment 30 coming into contact with the rod 27.

This delay is only for a brief instant, however, and is for the purpose of permitting the first bobbin of the compartment sufficient time to fall to the indicator door 37 and to cause it to open. As soon as the door is struck by the first bobbin the latch 21 is caused to pivot and the transverse rod 27 is engaged by the second abutment 29 and positively held at that position as shown in Fig. 3 while the abutment 30 is received in the recessed portion 26 of the cam 25. The stop means remains in this position until the supply of bobbins in the battery reaches a point which is below the lower end of the door 37.

When this takes place, the counterweight 38 moves the door 37 upwardly but the link member 31 is not actuated until the extension 42 is moved from the upper to the lower end of the slot 33 at which time the stop means is effectively released due to the sudden impact upon the link by the extension. This lost motion effect overcomes any tendency of the stop to remain engaged due to the weight of a part of the magazine bearing upon it. The transverse rod passes through the opening between the two abutments and the cycle is repeated at the next compartment of the magazine.

While one embodiment of the invention has been disclosed, it is to be understood that the inventive concept may be carried out in a number of ways. This invention

is, therefore, not to be limited to the precise details described, but is intended to embrace all variations and modifications thereof falling within the spirit of the invention and the scope of the claims.

5. We claim:

1. In combination with a loom for weaving, a bobbin feeding means for retaining and presenting for transfer to a loom shuttle a supply of bobbins having filling wound thereon and received from a magazine guided for travel above and in register with said feeding means, said magazine having its bobbins disposed in vertical tiers and means including a transverse rod for retaining each tier of bobbins, said rod being movable in inclined slots
10. magazine having its bobbins disposed in vertical tiers and means including a transverse rod for retaining each tier of bobbins, said rod being movable in inclined slots for releasing a tier, and means operable with said feeding means for stopping a magazine in position to discharge bobbins to the feeding means which includes latch means movable to two positions and effective for maintaining a tier of bobbins aligned with said feeding means in each of said two positions.
15. 2. In combination with a loom having a shuttle, a battery for holding a plurality of filling packages from which the loom shuttle is periodically replenished, means for automatically supplying filling packages to said battery which comprises an inclined supporting track, a compartmented container movable by gravity along said track and stop means at the track for engaging said container at each of two positions and effective for maintaining a compartment aligned with the first of said positions for a relatively short period of time and with the second of said positions for a relatively long period of time.
20. 3. The combination of claim 2 wherein said stop means comprises a pivoted latch element which is controlled by a filling supply actuated member at the entrance end of said battery.
25. 4. The combination of claim 3 wherein said latch element is actuated by means of a link member slotted at one end whereby positive displacement of said latch element is insured.
30. 5. In combination with a loom having a shuttle, a battery for holding a plurality of filling packages from which the loom shuttle is periodically replenished, means for automatically supplying filling packages to said battery which comprises an inclined supporting track, a compartmented container movable by gravity along said track and stop means at the track for engaging said container wherein said stop means comprises a pivoted latch element having two horizontally separated magazine engaging abutments.
35. 6. The combination of claim 5 wherein said latch element is actuated by means of a link member slotted at one end whereby positive displacement of said latch element is insured.
40. 7. The combination of claim 5 wherein said latch element is controlled by a filling supply actuated member at the entrance end of said battery.
45. 8. In combination with a loom having a shuttle, a battery for holding a plurality of filling packages from which the loom shuttle is periodically replenished, means for automatically supplying filling packages to said battery which comprises an inclined supporting track, a compartmented container movable by gravity along said track and stop means at the track for engaging said container wherein said stop means is effective to halt advancement of said container momentarily until at least one filling package has been released into the opening of said battery whereupon said stop is actuated to a second holding position.
50. 9. In combination with a loom for weaving, a bobbin feeding means for retaining and presenting for transfer to a loom shuttle a supply of bobbins having filling wound thereon and received from a magazine guided for travel above and in register with said feeding means, said magazine having its bobbins disposed in vertical tiers and means including a transverse rod for retaining each tier of bobbins, said rod being movable in inclined slots
55. 70. 75.

for releasing a tier, and means operable with said feeding means for stopping a magazine in position to discharge bobbins to the feeding means which includes latch means movable to two positions and having two horizontally separated abutments, a horizontally inclined fixed cam element adapted to be engaged by said rod to cause movement thereof rearwardly and upwardly in said inclined slots, said cam element having a recessed portion therein into which one of said abutments is movable upon actuation of said latch means to its second holding position.

10. In combination with a loom for weaving, a bobbin feeding means for retaining and presenting for transfer to a loom shuttle a supply of bobbins having filling wound thereon and received from a magazine guided for travel above and in register with said feeding means,

said magazine having its bobbins disposed in vertical tiers and means including a transverse rod for retaining each tier of bobbins, said rod being movable in inclined slots for releasing a tier, and means operable with said feeding means for stopping a magazine in position to discharge bobbins to the feeding means which includes latch means movable to two positions and having two horizontally separated abutments each of which is separately contacted by said transverse rod during the alignment of a single tier with said feeding means and between which said rod passes upon release of said latch means.
